COMBINATION VALVE

Courtland B. Currie, Los Angeles, Calif., assignor to Minneapolis-Honeywell Regulator Company, Minneapolis, Minn., a corporation of Delaware

Application November 15, 1955, Serial No. 546,852

2 Claims. (Cl. 236—48)

The invention described herein relates to control devices or combination valves of the type that embodies a plurality of valves for serving various functions. More particularly, the invention relates to the combination of a safety valve, a manually operable valve and a condition responsive valve all compactly arranged in a single housing in such a manner as to facilitate the use thereof.

The invention is primarily adapted to be used as a control for water heaters of the gas burning type and, since the space in which water heaters are generally located is quite small, it is highly desirable that the control for the water heater be as small as possible, be of pleasing appearance, and above all, safe and reliable in operation.

One of the objects of this invention is to provide a control device which will meet the above described specifications.

Another object of the invention is to provide a control device which incorporates a manually reset thermocouple safety valve, a manually operable plug valve for controlling the flow of gas from the inlet of the control to a pair of outlets, one to the main burner and one to the pilot burner, a thermostatically operated valve downstream of the plug valve, and a filter and adjusting valve in series and downstream of the plug valve and in the pilot burner line.

A further object of the invention is to provide a control device which may be easily manufactured and relatively inexpensive, yet sturdy in construction and reliable in operation.

A still further object of the invention is to provide in a substantially rectangular-shaped control housing, a pair of substantially parallel gas flow passages leading from a safety valve through a plug valve and to main burner and pilot burner outlets, so as to provide 100% safe shutoff of the gas and to provide a maximum rate of gas flow.

A further object of the invention is to provide a mounting bracket for a control device which will serve the function of sealing an opening in the control device, supporting the thermostatic or other condition responsive means and providing a guide for the valve actuated by the condition responsive means.

Still other objects of the invention will become apparent upon reading the following detailed description of the invention in conjunction with the accompanying drawings wherein:

Figure 1 is an elevational view of the control device or combination valve with portions thereof broken away and portions shown in cross section;

Figure 2 is a cross sectional view taken along the line 2—2 of Figure 1; and

Figure 3 is a cross sectional view taken along the lines 3—3 of Figure 1.

As can best be seen in Figure 3 of the drawing, the control device comprises a main body portion 11 having a chamber 12 opening to the rear of the body and a chamber 13 opening to the front of the body. The

2

body also has a stepped bore 14 (see Figure 1) intersecting a threaded inlet 15, a tapered bore 16 extending downwardly from the top surface of the body and opening into the chamber 13, a chamber 17 open at its side, and a stepped bore 18 (Figure 2) leading from the chamber 17 to a threaded outlet 19 which is adapted to be connected to a pilot burner. A threaded outlet 20 extends from the chamber 12 through the bottom wall of the body 11.

Intermediate the ends of the stepped bore 14, is a reduced diameter portion 14a which provides an annular shoulder 14b between the portion 14a and an intermediate diameter portion 14c extending to the top of the body 11. Positioned in the portion 14a, with a pressed fit, is a sleeve 21 which terminates at its lower end in a valve seat 21a and which has an external diameter portion 21b which rests against the shoulder 14b. The inner cylindrical wall portion of the upper end of the sleeve 21 serves as a valve seat for a piston valve to be described hereafter.

Threaded into the bottom open end of the bore 14 is an electromagnetic unit of conventional construction which includes an electromagnet (not shown) and a movable armature (not shown) that is connected to an axially slidable stem 23, which, in turn, is connected to a disk valve 24. The unit 22 is adapted to be connected to a thermocouple, shown schematically at T, the thermocouple being adapted to be heated by a pilot burner P which, in turn, is adapted to ignite a main burner B. A coil compression spring 25 normally biases the disk valve 24 into sealing engagement with the valve seat 21a and the armature (not shown) away from the electromagnet.

Threaded into portion 14c of the bore 14 is a hollow plug 26 having an apertured end 26a and an open upper end. A manually operable reset stem 27 extends through the aperture in the end 26a. A stem 27 carries at its upper end, a knob 28 having a skirt portion 28a which engages the upper end of the stem 27 and which carries a sleeve 29 surrounding the skirt portion 28a which, in turn, has a skirt portion 29a that extends into the hollow portion of the plug 26 to serve as guide means for the stem. The inner end of the stem 27 has an annular groove therein that retains an abutment washer 30. Spaced inwardly from the inner end of the stem 27, is an

interrupter valve" in the form of a flexible washer 31 which is adapted to fit snugly in the sleeve 21 as a piston to prevent the flow of gas through the sleeve before the end of the stem 27 engages the head of the valve disk 24 to move it to its "open" position. The washer 31 is maintained in its assembled position by means of a pair of axially slidable metallic washers 32, one located on each side thereof, a fixed washer 33 on the stem 27 above the washers 31 and 32, and a coil compression spring 34 extending between the abutment washer 30 and the lower one of the washers 32.

Positioned in the bore 16, is a rotatable plug valve 35 that has an axial bore 35a therein extending inwardly from the bottom end thereof and an intersecting radial bore 35b therein intermediate its ends which is adapted to register with a bore 11d extending from the tapered bore 16 to the portion 14c of bore 14, below the plug 26. Also formed in the outer periphery of the plug valve, is an arcuate groove 35c that is adapted to register with a bore 11e extending through a front wall of the body 11, and arcuate groove 11h, formed in the wall of the bore 6 and extending from the bore 11e toward but spaced from the bore 71, to provide gas flow to the pilot burner when the plug valve is in either its "on" position or its "pilot" position but not when the plug valve is in its "off" position. The gas flow from the inlet 15 to the arcuate groove 35c in the plug valve, is through a radial bore 21c extending from the interior

of the sleeve 21, through the sleeve 21 and a bore 11f through a front wall of the body 11 and terminating in a groove 11g formed in the outer face of the front wall of the body 11. The groove 11g extends from the bore 11f to the bore 11e.

A partition wall 11a separates the two chambers 12 and 13. It has a tubular opening 11b therethrough substantially at right angles to the front surface of the body portion 11 and an opening 11c therethrough near the outlet 20 which terminates in a valve seat on the chamber 13 side of the partition 11a.

A front cover plate 40 is secured to the body 11 by screws (not shown) with a gasket therebetween and over the groove 11g and around the periphery of the chamber 13 to thus form a gas-tight passage between the groove 11g and gasket 41 extending from the bore 11f to the bore 11e and to seal the chamber 13 from leakage to the atmosphere. The plate 40 also clamps a ring 42 of rubber or other suitable material against the front end of the tubular opening 11b in the partition 11a.

A disk valve 43 is held against a backing head 44 by means of a metallic washer 45. The washer 45 is biased against the disk valve 43 by means of a coiled compression spring 46 that has the other end thereof positioned in an annular groove in valve stem 44a. A coiled compression spring 47 is positioned between the plate 40 and the valve head 44 to normally bias the valve 43 into sealing engagement with the partition 11a around the opening 11c, serving as a valve seat.

The valve 43 is guided in its movement toward and away from the valve seat by means of a guide pin 48 having a plurality of longitudinally extending ribs thereon, which guide pin is rigidly secured in a mounting bracket 49 bolted to the rear side of the body 11. A gasket 50 is located between the bracket 49 and the periphery of the open side of the chamber 12. The guide pin extends through a valve actuating sleeve 51 and is axially slidably in a bore 44b of the valve stem. The guide also extends into a bearing sleeve 52 having a flange thereon that engages the closed end of the valve stem. A coiled compression spring 53 is adapted to provide friction between the valve stem 53 and the actuating sleeve 51. The outer end of the sleeve 51 has a flanged portion 51a that is adapted to be engaged by a snap disk 54 having a radially extending arm 54a that engages the portion 51a of the actuating sleeve 51. As can be seen from the drawing, the distance across, or the diameter of the flange 51a, is over one-third and nearly one-half of the distance from the center of the valve stem to the center of the snap disk.

The snap disk 54 is actuated by a fixed pivot member 55 abutting against bracket member 49 and having a shoulder portion 55a on which a central apertured portion of the snap disk 54 rests and a movable abutment member 56 that bears against the outer periphery of the disk 54 through a "spider" member, a disk having radially extending fingers of relatively heavy material and designated by the reference numeral 57.

Movable abutment 56 is actuated by a conventional rod and tube temperature responsive unit, generally designated by the reference numeral 58. It comprises a temperature responsive tube 59 anchored at its outer end, by an internally and externally threaded plug 60, to a small-diameter rod or wire 61. The inner end of the tube 59 is threaded into the bracket member 49 while the inner end of the rod 61 is threaded into an adjusting nut 62 bearing against the inner end of the movable abutment 56. The adjusting nut has diametrically opposed axially extending slots 62a therein which receive radially extending arms 63 on an adjusting stem 64.

The stem 64 has an enlarged diameter portion 64a that is rotatably located in the tubular portion 11b of the wall 11a. This enlarged diameter portion is also engaged by the sealing ring 42 between the plate 40 and the end of the wall portion 11b to provide a gas-tight

seal around the stem to prevent the leakage of gas from the chamber 12 to the atmosphere.

The calibration of the thermostatically controlled unit may be varied by means of a clamping screw 65 threaded into the outer end of the stem portion 64a and through a mounting sleeve 66 for a control knob 67. By loosening the screw 65, the sleeve 66 may be rotated with respect to the stem 64 and thereby change the calibration of the control. Tightening of the screw 65 will lock the mounting sleeve on the stem 64 by forcing the tapered bore of the sleeve 66 upon the tapered end of the stem portion 64a. It is to be noted that the knob 67 is secured to the sleeve 66 by means of a set screw 68 threaded radially into a threaded bore 69 in the knob. Obviously, the control point at which the rod and tube will actuate the snap disk to open the valve 43 may be varied by rotating the knob 67 and thus thread the adjusting nut 62 longitudinally of the rod 61 to vary the position of the movable abutment 56 with respect to the fixed abutment 55a.

While the gas for the main burner flows through the thermostatic valve 43 as described above, the gas for the pilot burner flows from the safety valve 24 through passages around the valve 31 and through arcuate passages 35c and 11h, formed in the walls of the valve 35 and the conical bore 16, and through bore 71 into chamber 17, through a filter 72. The filter is sealed around the outer end of the bore 71 by means of a rubber or other suitable material gasket 73, which is held firmly around the bore 71 by means of a fingered leaf spring 74. The spring is located between the outer side of the filter 72 and a cover plate 75, which is secured over the side opening of the chamber 17, with a gasket 76 therebetween, by means of bolts 77.

As can best be seen in Figure 2 of the drawing, gas, after it has passed through the filter 72, will flow around the outside of the filter 72 and out of chamber 17 through a vertical and stepped bore 18 and through an externally threaded clamp fitting 78 that is adapted to sealingly clamp a piece of tubing (not shown) leading to a pilot burner P. The bore 18 is intersected by a step bore 79 in which is rotatably mounted a slotted plug valve 80. By rotating the plug 80 to position varying amounts of the slot 80a across the bore 18, the rate of gas flow to the pilot burner may be adjusted. To provide for this adjustment, a threaded sealing plug 81, threaded into an outer threaded portion 79a of the bore 79, may be removed through an enlarged opening 75a in the cover plate 75, to expose the outer slotted end of the adjusting valve 80.

Operation

Should the control or combination valve be installed in a heating system such as a water heater, with the inlet 15 connected to a source of gas supply, the outlet 20 connected to a main burner B, the outlet 18 connected to a pilot burner P for igniting the main burner and heating a thermocouple T that is connected to the electromagnet 22, the unit 58 inserted in a water tank heated by the burner B, and with the elements of the control in the positions illustrated in the drawing, but with the valve 43 open and the slot 80a turned as to be in registration with bore 18, the heating system may be placed in operation by pressing inwardly on the button 28. This will bring the washer 31 into engagement with the upper end of the sleeve 21. Further inward movement of the button 28 will cause the washer 31 to flex and to seal the opening through the sleeve 21 and to bring the lower end of the stem 27 into engagement with the head of the valve 24. Still further movement of the button 28 will cause the valve 24 to be opened and the armature on the stem 23 to engage the magnet within the housing 22. At this point, gas may flow through the inlet 15, past valve 24, through the openings 21c and 11f, channel 11g, opening 11e, grooves 35c and 11h, opening 71, filter 72, chamber

17, valve slot 80a and outlet 18 to the pilot burner. Ignition of the pilot burner will cause heating of the thermocouple T so as to energize the magnet 22 to hold the valve 24 open. Return movement of the valve 31, by releasing the button 28, will then permit gas to flow through the sleeve 21, past valve 31, through passage 11d, bore 35b, bore 35a, chamber 13, past valve 43, through opening 11c, and out the outlet 20 to the main burner where it would be ignited by the pilot burner.

Gas will then continue to flow to the main burner under the control of the rod and tube thermostat to raise the water temperature in the tank to the desired temperature, at which point, the rod and tube are in a "satisfied" condition, that is, the water around the tube 59 is at or above the control temperature so that it has expanded and pulled the wire or rod 61 inwardly of the tube to move the abutment 56 to the left, as viewed in Figure 3, to cause the spider 57 to actuate the snap disk over center from its normal biased position and the arm 54a away from the actuating sleeve 51. This permits the spring 47 to move and hold the valve 43 against the valve seat.

Upon the water temperature dropping below the control point, the tube 59 will contract and cause the rod 61 to move the abutment 56 and the spider 57 toward the right, thus freeing the snap disk 54 to snap across center under its own bias and to move the arm 54a toward the right. As can be seen in the drawing, the arm 54a engages the head or flange 51a of the sleeve 51 at a point very near the periphery of the disk 54 at first. This permits the disk 54 to exert a much greater force on the sleeve 51 at first to break the valve 43 from the valve seat against the pressure of the gas. As soon as the valve is off the valve seat, less force is needed to move it to a further open position and, as the sleeve 51 moves toward the right, the arm 54a of the snap disk will rock across the head of the actuating sleeve to exert its opening force against the far edge of the head 51a. This gives a greater amount of movement of the valve by the snap disk to hold the valve in its wide open position.

The spring 53 while permitting adjusting movement of the sleeve 51 in the valve stem 44a, to vary the effective length thereof, frictionally holds them in adjustment while retaining bearing sleeve 52 in position.

To cut off main gas flow without cutting off the pilot gas flow, the plug valve 35 may be moved to the "pilot" position taking opening 35b out of registration with the opening 11d but leaving groove 35c in registration with opening 71 and groove 11h. Gas to both burners may be cut off by moving the plug valve to its "off" position where groove 35c is also out of registration with groove 11h or opening 71.

While I have described the preferred embodiment of my invention, it is to be understood that modifications

may be made in the preferred embodiment of the invention, by those skilled in the art, without departing from the spirit thereof. The scope of the invention must, therefore, be determined from the appended claims.

5 I claim:

1. A control device, comprising, a valve, means biasing said valve towards its "closed" position, said valve having a hollow stem closed at one end, a bearing sleeve in said stem at said closed end, a valve actuating sleeve adjustable in and extending beyond the open end of said stem and having a radially and outwardly extending flange thereon at its outer end, a compression spring between said bearing sleeve and said actuating sleeve for frictionally holding said actuating sleeve and said bearing sleeve in their assembled positions in said valve stem, a mounting bracket for the control device, said bracket carrying condition responsive means for actuating said valve, a guide pin for said valve supported by said bracket and extending through said actuating sleeve and into said bearing sleeve, said condition responsive means having a pivoted cantilever arm that engages the nearest edge only of said sleeve flange when said valve is in its "closed" position and the far edge only of said flange when said valve is in its "open" position.
2. A control device, comprising, a valve, means biasing said valve towards its "closed" position, said valve having a hollow stem closed at one end, a bearing sleeve in said stem at said closed end, a valve actuating sleeve adjustable in and extending beyond the open end of said stem and having a radially and outwardly extending flange thereon at its outer end, a compression spring between said bearing sleeve and said actuating sleeve for frictionally holding said actuating sleeve and said bearing sleeve in their assembled positions in said valve stem, a mounting bracket for the control device, said bracket carrying condition responsive means for actuating said valve, a guide pin for said valve supported by said bracket and extending through said actuating sleeve and into said bearing sleeve.
